THERMOSTAT MECHANISM

Earl K. Clark, Mansfield, Ohio, assignor to Westinghouse Electric & Manufacturing Company, East Pittsburgh, Pa., a corporation of Pennsylvania

Application December 23, 1939, Serial No. 310,680

4 Claims. (Cl. 200—140)

My invention relates to thermostat mechanisms and has for an object to provide an improved mechanism of this kind.

A further object of my invention is to provide an improved thermostat of the expansible fluid type wherein friction in the leverage system between the expansible element and the control means actuated thereby is maintained at a minimum.

A still further object of the invention is to provide improved apparatus of the character set forth which may be readily manufactured and calibrated, the adjusting member of all thermostats being uniformly positioned relative the heat-responsive element and the control device actuated thereby.

It is a still further object of my invention to provide an improved thermostatic switch structure adaptable for two-pole construction and wherein creep action of the contacts is prevented during opening and closing movements thereof.

It is a still further object of my invention to provide an improved thermostat of the fluid type for controlling the temperature of an oven wherein the bulb of the thermostat is rigidly positioned in the oven in a predetermined position and wherein damage to the capillary tube at the point where it enters the oven is prevented.

These and other objects are effected by my invention as will be apparent from the following description and claims taken in accordance with the accompanying drawings, forming a part of this application, in which:

Fig. 1 is a partial front view of an electric range having my improved thermostatic control apparatus applied thereto;

Fig. 2 is a section taken on the line II—II of Fig. 1;

Fig. 3 is a partial front view of another form of electric range having my improved control apparatus applied thereto;

Fig. 4 is a section taken along the line IV—IV of Fig. 3;

Fig. 5 is a sectional view taken on the line V—V of Fig. 1;

Fig. 6 is a sectional view of a detail shown in Fig. 5;

Fig. 7 is a front view of the apparatus shown in Fig. 6;

Fig. 8 is a longitudinal sectional view of a thermostat constructed in accordance with my invention;

Fig. 9 is a front view of the apparatus shown in Fig. 8 with portions removed for the sake of clearness;

Fig. 10 is a sectional view taken along the line X—X of Fig. 9;

Fig. 11 is a view of a detail shown in Fig. 8 looking from the plane XI—XI;

Fig. 12 is a longitudinal sectional view of a modified form of thermostat shown in Fig. 8 with parts removed for the sake of clearness;

Fig. 13 is a diagram of the spring forces of various elements shown in Fig. 12; and,

Fig. 14 is a wiring diagram for the oven element of the ranges shown in Figs. 1 and 3.

Reference will now be had to Figs. 1 and 2 wherein I have shown my improved thermostat applied to an electric range 10 having an oven portion 11, and a cooking surface 12, the latter being provided with a plurality of surface heating elements, one of which is shown at 13. The range 10 includes a back splasher 14 which supports a plurality of switches 15, the latter controlling energization of their respective heating plates 13. The back splasher 14 also defines the support for the thermostatic control mechanism, generally indicated at 16, and including a manually operated switch 17 and a thermostat 18, the latter being constructed in accordance with my invention. The manually operated switch 17 and the thermostat 18 are connected by a tie member 19 so that they define a unitary structure which is supported by the back splasher 14 of the range. The construction of the thermostatic switch mechanism 18 and the manual switch 17 as a unit is described and claimed in a copending application of E. K. Clark and J. S. Wojcik, Serial No. 309,922, filed December 19, 1939 and assigned to the assignee of the present application.

As best shown in Fig. 2, both the manually-operated switch 17, which is of the rotary type, and the thermostat 18 are actuated by a common knob 21. Preferably, the knob 21 carries an index 20 which registers with indicia on the range, which indicia includes an "off" position and several temperature settings. A pulley 22 is rotatably mounted with the knob 21 and is connected by means of a belt 23 to a second pulley 24 carried by an adjusting stem 25 of the thermostat 18. I have described in detail hereinafter the mechanism for effecting the adjustment of the thermostat 18.

The manually-operated switch 17 and the thermostat 18 control energization of a heating element diagrammatically shown at 11a and disposed within the oven 11. The switch 17 defines a line switch for positively opening and closing the circuit of the element 11a and the thermo-

stat 18 which is connected in series with the switch 17 also energizes and deenergizes the heating element automatically to provide a predetermined mean temperature within the oven. The electrical connections between the switch 17, the thermostat 18 and the element 11a are clearly shown in Fig. 14 and need not be further described. It will be understood that the manual switch is open in the "off" position and is closed when the knob 21 is adjusted to any temperature position.

The thermostat 18 is of the hydraulic type and includes an expansible element 26 formed of spaced flexible walls 27 secured at their peripheries and enclosing the intervening chamber 28 (see Fig. 8). The chamber 28 communicates by means of a capillary tube 29 with a bulb 31 disposed within the oven 11 as best shown in Fig. 5. It will be apparent that the walls 27 of the expansible element 26 are closely spaced so that a small amount of fluid is contained therein; the major portion of the fluid being at all times contained within the tube 29 and the bulb 31. The disposition of the thermostat on the range 10 in both Figs. 1 and 3 is such that the expansible element 26 is not affected substantially by the heat of the oven or any extraneous source of heat, being at all times in an atmosphere whose temperature does not increase materially above that of the room in which the range is installed. As the variations in room temperature are relatively small, no compensation of the thermostat in response to such variations is necessary to provide the proper desired mean temperatures in the oven. In this connection, it will be understood that, where the expansible element is arranged so that transfer of an appreciable amount of heat from the heating elements of the range to the expansible element of the thermostat is effected, compensation of the thermostat must be provided. In accordance with this invention, I provide a thermal-responsive element wherein the amount of fluid in the expansible element during periods of maximum oven temperature does not exceed 10% of the total amount of fluid in the enclosed system. With this proportioning of the fluid in the enclosed system, very little change in the volume of the fluid because of ambient temperature changes is effected and, therefore, I have found that compensation of the thermostat for ambient temperature variations may be omitted.

Referring now to Fig. 5, the numeral 32 indicates an oven lining surrounded by heat insulation 33, which oven lining 32 includes an end wall 34, at its rear side. An opening 35 is provided in the end wall 34 through which the bulb 31 and the tube 29 are passed during their assembly to the oven lining 32. The bulb is secured to the side wall of the oven lining 32 by means of brackets 36 which are arranged adjacent the side of the oven and in an upper region thereof, at which location the bulb 31 and the fluid contained therein quickly respond to temperature changes of the air within the oven lining 32.

In accordance with my invention, a collar 37 is brazed or otherwise fixed to the tube 29 a predetermined distance from the bulb 31. The collar 37 has relatively large end portions 38 and an undercut intermediate portion 39 which is adapted to rest on the bottom of the opening 35 formed in the oven liner 32. It will be understood that the opening 35 in the oven is sufficiently large to permit the passage of the bulb 31 and the inner enlarged end portions 38 of the

collar 37 during assembly of the thermostatic bulb to the oven. After assembly, the plate 41 is secured to the end wall 34 in any suitable manner such as, for example, by means of a self-tapping screw 42. The plate 41 closes the opening 35 and also bears on the collar 37 for maintaining it in fixed position. In accordance with this construction, the tube 29 is protected from injury during assembly or during operation. The collar 37 protects the tube 29 from abrasion or other mechanical injury which is possible where an unprotected tube is passed through an opening in the oven. It will be apparent from the foregoing description that the collar 37 not only protects the tube 29 which is usually formed of a soft material but also serves as an index for positively locating the bulb 31 in a predetermined location longitudinally within the oven.

Reference will now be had to Figs. 3 and 4 which show another type of range having my improved thermostatic control mechanism applied thereto. The range 10 shown in Fig. 3 is somewhat similar to the range shown in Fig. 1 and includes an oven 11; a back splasher 14 and a cooking surface 12, the latter serving to support the plurality of hotplates 13 in the same manner described heretofore. In this embodiment, the switches for controlling the hotplates 13 are shown at 15 and supported on a lower front wall 43 of the range. The thermostatic controlling mechanism, including a manually-operated switch 44 of the rotary type and a thermostatic controller 45 similar in construction to the thermostat 18, is arranged beneath the cooking top 12 and in line with the switches 15. As best shown in Fig. 4, the switch 44 and the thermostat 45 are actuated to their various positions by a common operating knob 46 secured to the shaft 47 of the switch 44. A second shaft 48 is connected by means of a coupling 49 to the shaft 47 and is rotatable therewith, the shaft 48 including a bifurcated member 51 which extends within openings 52 formed in the rotatable member 53. The rotatable member 53 is connected to the adjusting stem 54 of the thermostat 45 for rotating the same during an adjustment of the thermostat. The rotatable member 53 may be formed as a pulley so that it can be used in conjunction with the bifurcated member 51 when assembled to a range in accordance with Fig. 3 or may serve as a pulley when used as shown at 16 in Fig. 2.

The thermostat 45 shown in Fig. 4 is secured by means of a bracket 55 to a wall member 56 adjacent the rear of the range 10 shown in Fig. 3, while the adjusting knob thereof is mounted exteriorly of the front panel 43 of the range. The thermostats 45 and 18 are of the same construction, so that a description of the thermostat 18 which appears hereinafter will suffice for both. The capillary tube 29 of the thermostat 45 may be extended to within the oven 11 in the same manner as described hereinbefore.

It will be apparent from an inspection of Figs. 1 to 4 that, in both embodiments, the thermostat mechanisms 18 and 45 are remotely disposed both with respect to the oven and with respect to the surface plates 13; it being apparent that only the heat-responsive bulbs 31 are subjected to any source of heat. As set forth heretofore, no compensating provisions responding to ambient temperature changes are necessary as part of the thermostat structure.

Reference will now be had to Figs. 8 to 11, inclusive, wherein I have shown the switching and operating mechanisms of my improved thermo-

stat which, it will be understood, is the same regardless of whether the thermostat is assembled to the back splasher of the range as shown in Fig. 2 or whether it is carried by a rear portion thereof as shown in Fig. 4.

Referring particularly to Figs. 8 and 9, the thermostat 18 includes a body portion 57 preferably formed of molded insulating material. A supporting frame 58 is attached in any suitable manner to one side of the body portion 57 and serves to support the various movable elements in the thermostat to be described hereinafter. To the opposite side of the body portion 57 is secured a cover such as the tie member 19 when assembled, as shown in Fig. 2.

The lower wall 27 of the expansible element 26 has a stud 61 secured to the central portion thereof, which stud is hollow and communicates with the tube 29. The stud 61 is supported by a cover 62 which is secured in any suitable manner, as for example, by means of screws 63 to the frame 58 and body portion 57. The chamber 28 within the expansible element 26, the hollow stud 61, the tube 29 and the bulb or reservoir 31 define a closed chamber which is entirely filled with an expansible liquid, the volume of which increases and decreases with increases and decreases in temperature. Any suitable fluid may be employed which retains its liquidity up to temperatures of 600° F. or the maximum temperature at which the oven is operated.

The switching mechanism associated with the thermostatic structure 18 will now be described. This mechanism is best illustrated in Figs. 8 to 10, inclusive and is of the double-pole, double-break type. The switch mechanism includes in one pole thereof, a pair of stationary contacts 64 and 65, the former of which includes a longitudinally-extending portion 66 carried by the body 57 and positioned thereon by means of a rivet 68. The outer end of the longitudinally-extending portion 66 of the contacts 64 is provided with a terminal screw 69 for connection to the electrical conductors. The contact 65 has a longitudinally-extending portion 71 which overlies the portion 66 of the contact 64 and is insulated therefrom by means of an insulating strip 72. The contact portion 71 is provided with an eyelet 73 which extends through openings in the conducting strip 72 and terminal portion 66 to the lower side of the body 57 and is provided with a terminal screw 74 for connection to the electrical conductor. The eyelet 73 is insulated from terminal 66 by the base member 57 which may include a boss 75 that extends into an opening formed in the contact terminal portion 66. The opposite pole of the switching mechanism includes stationary contacts 76 and 77, which are connected to terminals in the same manner as described in connection with the contacts 64 and 65 so that a further description of the stationary contact structures 76 and 77 is deemed unnecessary.

Movable contacts 78 and 79 associated with the opposite poles of the switch are engageable with their respective stationary contacts. The movable contacts 78 and 79 are carried by an insulating bridge 81 which is disposed beneath a transverse strut 82, the latter being secured to the body 57 at its end by means of screws 83. The strut 82 carries a pair of stops 84 which are defined by studs 85 screwed into the strut 82 and locked in place by means of lock nuts 86, see Fig. 10. The studs 85 limit the upward movement of the bridge 81 and, therefore, the gap between

5 the movable contacts and their respective stationary contacts in switch-open position. As best shown in Fig. 10, the movable contacts 77 and 78 are closely carried by pins 87 which are driven into the insulating bridge 81 and permit limited rocking movement of the contacts 77 and 78 relative the bridge 81 in a plane longitudinal to the terminals 66 and 71. Accordingly, good contact between the movable contacts 77 and 78 and their stationary contacts is provided at all times.

10 Movement of the expansible member 26 is imparted to the switching mechanism by means including a plurality of levers which will now be described. The switch-operating leverage system includes a main switch arm structure 88 which includes a swivel 89 pivoted at 91 to arms 92 forming a part of the frame structure 58. The main switch arm 88 includes also a resilient switch arm 93 secured to the swivel 89 in any suitable manner, such as, for example, by rivets 94 and is provided at its free end with a pair of points 95, the latter being seated in indentations 96 formed in one leg of the spring 97 of U-shape as viewed in Fig. 8. The opposite leg of the spring 97 is provided with an indentation 98 for receiving an adjustably-pointed screw 99 carried by the frame structure 58.

15 As described more in detail hereinafter, the spring 97 functions as a snapover spring for effecting quick opening and quick closing of the switching mechanism. The pointed screw 99 is threaded into a plate 101 and locked thereto by means of a lock nut 102, the plate 101 being secured to the frame 58 by means of screws 103 which extend through elongated openings 104 formed in the plate 101. In accordance with this construction, the plate 101 and the needlepoint screw 99 may be adjusted upwardly and downwardly for adjusting the relative amount of travel of the switch arm 88 each side of its dead-center position. The needlepoint screw 99 may be adjusted inwardly and outwardly relative to the plate 101 for varying the bias of the U-shaped spring 97.

20 Movement of the switch arm 88 is imparted to the insulated bridge 81 and the movable contact 78 by means of a link 105 loosely carried by the resilient arm 93. As shown, a pair of studs 100 extend through holes in the link 105 and position the same, which studs 100 are secured to the resilient arm 93 in any suitable manner. In accordance with this construction, limited movement of the link 105 relative to the arm 93 in switch-opening and switch-closing direction is provided. An upwardly-extending portion 106 is formed on the link 105 and extends into an opening 107 formed in the insulated bridge 81, the upwardly-extending portion 106 having a suitable opening therein for receiving a pin 108 which is securely driven into the bridge 81. The connection between the pin 108 and the portion 106 of the link 105 is such as to afford some limited rocking motion of the bridge 81 relative the link 105 so that the pressures on the movable contacts 78 and 79 are substantially equalized regardless of any inaccuracy in assembly of the apparatus.

25 The link 105 is biased toward the resilient arm 93 at all times by a spring 109, one end of which bears against the resilient arm 93 and the opposite end of which rests on the seat 111 formed on a stud 112, the latter extending through a suitable opening in the resilient arm 93 and being riveted or otherwise secured to the

link 105. The spring 109 may be termed a follow spring which assures positive opening and closing of the switch contacts and prevents any creep action therebetween in the switch-closed position as shown in Fig. 8, the follow spring 109 is compressed and the resilient arm 93 engages a shoulder 110 formed on the stud 112. The contacts are held closely in engagement by the bias of the spring 97 acting through the arm 93. The spring 109, in this position, impresses a slight bias upon the resilient arm 93 in switch-opening direction but it is relatively small compared to the force of the spring 97.

When the switch arm 93 is moved upwardly in switch-opening direction, the space between the link 105 and the resilient arm 93 is first closed, and, after engagement of these elements, the switch is moved in opening direction. During the first portion of this movement, pressure is maintained between the movable contact and the stationary contacts by the spring 109. Acceleration of the lever 93 is rapid as described hereinafter as the space intervening between it and the link 105 is closed so that, after engagement of these elements, the movable contacts are disengaged from their stationary contacts in a snap-acting manner. It will be noted, that pressure between the movable and stationary contacts is maintained continuous by the spring 109 until the moment of separation. When actuated in the closing direction pressure between the movable and stationary contacts is established as soon as they engage, as the bias of the spring 109 is effective immediately upon separation of the link 105 and arm 93. Full pressure on the contacts is, of course, effective upon engagement of the arm 93 with the shoulder 110 of the stud 112.

Movement of the expandable element 26 is imparted to the switch arm 88 through the medium of a lever 113 pivoted at 114 to arms 115 carried by the frame structure 58. As best shown in Figs. 8 and 11, the lever 113 includes side portions 116 having a web portion 117 extending therebetween, the latter being engageable with one or more protuberances 118 formed on the underside of the switch arm structure 88. Preferably, the protuberances 118 are formed by embossing the resilient arm 93 as shown. A center portion of the web 117 is cut away as shown at 119, the opposite sides of the cutaway portion 119 forming knife edges 121 for a purpose to be described hereinafter.

Clockwise movement of the lever 113 about its pivot 114 effects counter-clockwise movement of the switch arm 88 about its pivot 91, and vice versa, it being understood that the web 117 is maintained continuously in engagement with the protuberances 118. In this connection, a compression spring 122 is disposed between the swivel 89 and the fixed portion of the structure, for example, the body 57, for continuously biasing the switch arm 88 in clockwise or the switch-closing direction. In order to reduce to a minimum the amount of friction between the lever 113 and the switch arm structure 88, I arrange their pivotal supports and the point of engagement of the web 117 and protuberances 118 in a straight line. Accordingly, these engaging members move substantially linearly and there is very little movement or slipping of the protuberances 118 relative to the surface of the web 117 during movement of the lever 113.

Movement is imparted to the lever 113 through its knife edges 121 which bear upon spaced portions of one side of a washer 123 that is carried by 76

an adjusting stem 124, the latter being moved axially as the expandable element 26 expands and contracts. The stem 124 is threaded within a cup 125 which is welded or otherwise secured to a central portion of the upper diaphragm 27 of the expandable element 26. A shoulder 126 is formed on the stem 124, preferably integrally, and functions as a stop for a second washer 127 carried on the stem 124 and juxtaposed with respect to the washer 123. Both washers 123 and 127 are provided with openings through which the stem 124 projects, said openings being somewhat oversize as to allow axial movement and limited rocking movement of the washers upon the stem. A relatively heavy compression spring 128 continually biases the stem 124 and the cup 125 apart, said spring bearing at one end upon the washer 123 and its opposite end upon a fixed shoulder 129 formed on the cup 125.

In order that the pressure on the transversely-spaced knife edges 121 may be maintained substantially equal, I provide a pair of diametrically-spaced protuberances 131 on the side of the washer 127 which is adjacent the washer 123. These protuberances bear upon the washer 123 and are spaced substantially 90° from the point of engagement between the washer 123 and the knife edges 121. Accordingly, any tendency of the washer 123 to bear unevenly upon the knife edges is counteracted by the protuberances 131 which permit slight rocking movement of the washer 123 in the plane of the knife edges. In order that the protuberances 131 remain substantially 90° from the knife edges 121, a pair of ears 132 are formed on the washer 127 and extend in an axial direction alongside of the portion of the web 117 which defines the knife edges 121. This construction is best shown in Figs. 8 and 11. Sliding of the knife edges 121 upon the surface of the washer 123 is minimized by arranging the pivot of lever 113 in the plane of said surface of the washer 123 so that movement of the knife edges and the washer 123 is substantially linear.

Adjustment of the thermostatic structure is effected by rotating the stem 124 or threading it inwardly and outwardly of the cup 125. These operations increase or decrease the distance between the washer 123 and the expandable element 26 so that more or less expansion is required to open and close the switch, depending upon the distance between these elements. Rotating the stem 124 to thread the same outwardly of the cup 125 increases the distance between the washer 123 and the expandable element 26 so that less expansion of the element 26 is required to operate the switch and, therefore, the switch is opened and closed at relatively low temperatures. Reducing the distance between the washer 123 and the element 26 necessitates greater expansion of the element 26 to operate the switch so that the oven is, therefore, operated at a relatively high mean temperature. It will be understood that the compression spring 128 is relatively heavy and sufficient at all times to overcome any bias imposed by the springs 122 and 97. Accordingly, the spacing of the washer 123 relative to the element 26 is unchanged for a given adjustment during all normal operations. If, however, for any reason, the element 26 would continue to expand subsequent to a switch-opening movement of the mechanism, the compression spring 128 would compress somewhat in order to prevent any damage to the leverage system or the expandable element.

Expansion and contraction of the compression

spring 128 is effected during periods of adjustment of the stem 124. When the mechanism is adjusted to a lower temperature setting from a higher temperature setting, during periods when the expansible element 26 is expanded, the switch would first be opened if in the closed position by the expansion of the spring 128 acting through the leverage system. With the switch in the open position further adjustment of the stem 124 would move the shoulder 126 thereof away from the washer 123, it being understood that the lever 113 at this time would prevent any axial movement of the washer 123. Contraction of the expansible element 26 would first engage the shoulder 126 and the washer 127 and, after engagement of these elements, would effect movement of the washer 123 and the leverage system. An adjustment of the mechanism from a lower temperature setting to a higher temperature setting compresses the spring 128. If the switch at this time is in the open position, it may be closed because of movement of the leverage system, the lever 113 of which follows the washer 123 as it is moved axially. Further adjustment of the stem 124 with the switch closed would, of course, relieve the spring force in the leverage system to a value below that necessary to close the switch. Subsequent heating and expansion of the expansible element would increase the spring force in the leverage system sufficiently to effect operation of the switch at the higher setting.

As set forth heretofore, adjustment of the mechanism is effected by rotating the stem 124. It will be apparent that the means for turning the stem 124 must provide for axial movement as this stem is moved axially during operation of the thermostat and during an adjustment thereof. As shown in Fig. 8, the pulley 24 is employed for rotating the stem 124 and, accordingly, is loosely carried upon the stem 124 so that the latter may move axially relative the pulley. Rotation of the stem 124 is effected by a plurality of projections 133 formed on a surface of the pulley and disposed on opposite sides of a pin 134 which extends radially through the stem 124 and secured in position by means of a nut and lock washer construction 135. As the pulley 24 and the projections 133 rotate about the stem, the projections engage the pin 134 and effect turning of the stem 124. It will be apparent also that the pin 134 may move axially between the projections 133 at this time. Limited movement of the pulley 24 about its axis is provided by a stop 136 which is engageable with a projection 137 formed on the periphery of the pulley. The driving means for the stem 124 and the stop construction just described is described and claimed in said copending application of E. K. Clark and J. S. Wojcik, Serial No. 309,922, filed December 19, 1939.

Uniform adjustment of large numbers of thermostats in production may be effected by providing adjustment between the expansible element and the switching mechanism independently of the operator's adjustment described heretofore. Accordingly, the expansible element 26 and the stud 61 thereof are rotatable in the cover 62 for providing axial movement of the stem 124 through its threaded connection to the cup 125. The pin 134 may be held in a predetermined position and the element 26 rotated for effecting operation of the switch at some predetermined temperature such as the mid temperature in its operating range. The expansible element may then be locked in place by a lock nut 60. All thermostats in production will, therefore, be uniform;

the position of their adjusting stems 124 relative the temperatures at which the switches are operated being identical for all thermostats.

As shown in Figs. 8 to 10, the thermostatic mechanism is in its switch-closed position and, therefore, heating of the oven is effected as the temperature of the oven and the temperature of the fluid within the bulb 31 increase, the expanding fluid moves the stem 124 and the washer 123 axially so that the lever 113 is moved in clockwise direction. Accordingly, the switch arm swivel 89 is biased in counter-clockwise direction in opposition to the bias of the springs 122 and 97. All members of the movable elements are deflected including the expansible element 26, its adjusting screw assembly 124-125, the lever 113 and the switch arm structure 88 at this time. The increase in bias because of this deflection progressively increases.

At this time it will be understood that the resilient arm 93 is also biased toward the switch-open position by the follow spring 109. When the force developed in the spring arm 93 at the spaced points 96 is sufficient to overcome the bias of the U-shaped spring 97, movement of the resilient arm 93 to its switch-open position is initiated. Acceleration of the resilient arm 93 is rapid as the effective force or turning moment of the spring 97 is progressively reduced as it approaches its dead center position. The small bias imposed by the spring 109, of course, is rendered ineffective when the resilient arm 93 engages the connecting link 105 but may be disregarded as it is of small value compared to the forces of the leverage system including the resilient arm 93 and the opposing force of the spring 97. The force at the spaced points 96 is reduced during this transition but it varies at a much lower rate than the reduction in force or turning movement of the spring 97. After passing through the dead center position, the spring 97 assists the resilient arm 93 in moving the switching mechanism to its open position. At the time of opening of the contacts, movement of the resilient arm 93, the connecting link 105 and the switch contacts is very rapid.

During the switch-open period, the temperature of the oven and of the fluid within the bulb 31 is reduced because of heat leakage from the oven, so that contraction of the fluid within the thermostatic element is effected. Accordingly, the stem 124 and the washer 123 are moved downwardly because of the bias of the spring 122 which acts upon the washer through the main switch arm swivel 89 and the lever 113. Movement of the swivel 89 in switch-closing direction increases the bias of the resilient arm 93 and, when the bias thereof overcomes the turning movement of the spring 97, movement of the switch in closing direction is initiated.

As set forth heretofore, the turning moment of the spring 97 rapidly reduces as it approaches dead center, so that acceleration of the resilient arm 93 is rapid. The movable contacts of the switch at the time of closing are moving at high speed. After passing dead center, the resilient arm assisted by the U-spring 97 continues its travel to the position shown in the drawings, during which time the follow spring 109 is compressed. The pressure between the movable contacts and their respective stationary contacts is maintained substantially equal because of the loose connection between the insulating bridge 81 and the connecting link 105. Furthermore, as set forth heretofore, the contacts are always

maintained under pressure when engaged at least to the extent of the pressure imposed by the follow spring 109. Creep action of the contacts is, therefore, precluded by the spring 109.

A further embodiment of the thermostatic switch structure is shown in Figs. 12 and 13. The thermostat, as shown in Fig. 12, is substantially the same as that shown in Fig. 8 and similar numerals for the common parts thereof are employed in both figures. The embodiment shown in Fig. 12 differs from that shown in Fig. 8 in that the compression spring 122 is eliminated and the U-shaped spring 97 so positioned relative the pivot 91 of the main switch arm that it imposes a bias at all times upon the resilient member 93 of the main switch arm 88 in switch-closing direction. In other words, the U-shaped spring 97 operates at all times on one side of its dead-center position.

The operation of the thermostat shown in Fig. 12 may be best understood by referring to the spring diagram of Fig. 13. It will be assumed that the switch shown in Fig. 12 is just closed and heating of the oven is initiated. At this time, the switch-opening bias of the leverage system including the resilient arm 93 is somewhat under three ounces, measured at the switch contacts, as shown at A in Fig. 13. The switch-closing bias of the U-shaped spring 97 is in excess of four ounces, as shown at B. The bias of the spring 109 is relatively small, of the order of one-third of an ounce, measured at the switch contacts, as shown at C. Of course, the bias of the spring 109 supplements the bias of the switch arm so that the total bias in switch-opening direction at this time is slightly over three ounces.

During the heating period, the leverage system is deflected and the bias of the resilient arm 93 increases to point D, at which time the combined bias of the resilient arm 93 and the spring 109 exceed slightly the bias of the spring 97, which is indicated at B. Accordingly, the main switch arm 88 initiates its movement toward the switch-open position, the progressive reduction in force imposed by the spring 97 being shown by the line E in Fig. 13. As the resilient arm 93 moves in switch-opening direction, its bias is reduced progressively, as shown by the line F. Midway of the switching gap, the resilient arm 93 and the connecting link 105 are engaged, as set forth heretofore, so that the bias imposed by the spring 109 is terminated, as shown at G on the diagram. At this time, however, it will be apparent that movement of the switching mechanism toward its open position is not substantially affected, as the force imposed by the spring 97 is considerably below the force imposed by the main switch arm 88, as shown at H. Accordingly, the switch rapidly continues its movement toward the open position.

In the open position of the switch, the force imposed by the spring 97 is indicated at J on the diagram, while the force imposed in switch-opening direction by the main switch arm 88 is shown at K. As the temperature of the oven decreases, the bias of the main switch arm structure 88 is progressively reduced from the point K to slightly below the point J on the diagram, at which time movement of the switch in closing direction is initiated. The force imposed by the spring 97 rapidly builds up while the bias of the main switch arm 88 increases at a lesser rate, so that the switch is rapidly accelerated during its movement to the switch-closed position. Midway of the switching gap, the bias of the spring

109 again becomes effective, as shown by the line L. In the closed position of the switch, the bias imposed by the main switch arm 88 is indicated at A and the force imposed by the spring 97 is indicated at B.

From the foregoing description it will be apparent that the spring 97 continuously biases, at all times, the main switch arm 88 in switch-closing direction and that the snap-acting movement 10 of the switch is effected because of the rapid reduction or increase in the effective turning moment of the spring 97 during movements of the switch.

The specific spring values set forth in Fig. 13 15 is shown by way of example, and has been taken from tests conducted upon one switch constructed in accordance with my invention. The pressures referred to were taken at the switch contacts as a matter of convenience, and the corresponding pressures at the adjusting stem 124 are indicated in pounds at the right-hand side of the diagram 13. It will be apparent that a pressure of one ounce at the contact corresponds to a pressure of approximately 30 ozs. at the adjusting stem, which is a ratio of approximately thirty to 25 one. It will be apparent that, for one unit of movement at the expansible element 26, 30 units of movement are obtained at the switch contacts.

From the foregoing description it will be apparent that I have provided improved thermostatic apparatus of the expansible fluid type 30 wherein the amplitude of movement of the switch is high relative the movement of the expansible element and wherein friction in the multiplying leverage system is reduced to a minimum. 35 The arrangement of the thermostat on the apparatus to be controlled and the construction of its expansible member are such that compensation for ambient temperature changes is obviated.

40 While I have shown my invention in several forms, it will be obvious to those skilled in the art that it is not so limited, but is susceptible of various other changes and modifications without departing from the spirit thereof, and I desire, therefore, that only such limitations shall 45 be placed thereupon as are specifically set forth in the appended claims.

What I claim is:

50 1. In a thermostat, the combination of an element movable in response to changes in temperature, a switch actuated thereby, means for transmitting movement of the element to the switch and including a stem movable in an axial direction by the expansible element, an arm having a pivot, the axis of which is spaced from the axis of the stem and disposed substantially at right angles thereto, said arm having a pair of laterally-spaced knife-edge portions, a collar having a surface extending substantially normal 55 to the axis of the stem and engageable with the knife-edge portions of said arm, said collar being arranged substantially coaxial with respect to the stem, and means for positioning the collar upon the stem and affording limited rocking movement of the collar relative to the stem, whereby the pressures between the knife edges and the respective portions of the collar engaged thereby are maintained substantially equal.

60 2. In a thermostat, the combination of an element movable in response to changes in temperature, a switch actuated thereby, means for transmitting movement of the element to the switch and including a stem movable in an axial direction by the expansible element, an arm hav-

ing a pivot spaced from the axis of the stem and extending substantially at right angles thereto, a shoulder carried by the stem, a collar engageable with the shoulder and having spaced protuberances formed on a face thereof, a second collar carried by the stem, means for biasing said second collar into engagement with said protuberances, said arm having a pair of laterally-spaced knife-edge portions engaging portions of the second collar, and means for maintaining said protuberances aligned substantially at right angles to a line extending through said knife edges.

3. In a thermostat, the combination of a fluid-containing element having a diaphragm portion movable in response to temperature changes, an internally-threaded cup secured to the diaphragm and movable in an axial direction therewith, a stem threaded within the cup, a shoulder carried by the stem and engaging said shoulder, said washer having a pair of spaced protuberances carried on a face thereof, a second washer slidably and loosely carried by the stem, said second washer having a face thereof engaging said protuberances whereby limited rocking of the second

washer upon the protuberances is afforded, biasing means interposed between said cup and the second washer, a switch, means for transmitting movement of said diaphragm to the switch and including a pivoted arm having spaced knife-edge portions in engagement with spaced regions of said second washer, and means for rotating the stem for adjusting the temperatures at which the fluid-containing element operates the switch.

4. In a thermostat, the combination of a wall member having an opening therein, a control device, a fluid-containing heat-responsive element for actuating said control device and arranged on one side of the wall member, said heat-responsive element including a capillary tube extending through said opening and an elongated bulb, means for positioning said bulb on the opposite side of the wall member, a sleeve fixed to said tube a predetermined distance from said bulb, said sleeve having a portion thereof resting upon a side of the opening in the wall member, and a clip secured to the wall member for closing the opening therein and engaging said portion of the sleeve, whereby movement of the sleeve within the opening is prevented.

EARL K. CLARK.
